UNITED STATES PATENT OFFICE.

LOREN L. WHITNEY, OF HAMMOND, INDIANA, ASSIGNOR TO AMERICAN STEEL FOUNDRIES, OF CHICAGO, ILLINOIS, A CORPORATION OF NEW JERSEY.

METHOD OF MAKING EQUALIZERS.

Application filed May 13, 1925. Serial No. 29,872.

This invention relates to a method for making an equalizer, and more particularly what is known as a horizontal equalizer body used in clasp brake equipment.

One object of the invention is to provide a simple, reliable and efficient method for making an equalizer whereby the number of steps is reduced and simplified.

Another object is to provide a simple and efficient method for forming the jaws at the ends of a horizontal body equalizer used in clasp brake equipment.

Another object is to provide a method for forming a horizontal equalizer used in clasp brake equipment and adapted to meet all of the requirements in forging operations.

These and other objects are accomplished by means of the method disclosed on the accompanying sheets of drawings, in which—
20 Figs. 1, 2 and 3 are respectively top, side and end views of a blank out of which the equalizer is made;

Figs. 4, 5 and 6 are respectively top, side and end views of one end of the blank after 25 it has been drawn out by the use of hammer dies, as shown in Figs. 19 and 20;

Figs. 7, 8 and 9 are respectively top, side and end views of the same end of the blank after it has been subjected to an upsetting 30 action in the forging machine dies shown in Figs. 21 and 22, it being understood that during this operation the blank was located in the lower portion of the dies shown in said figures and the plunger shown in Fig. 35 24 was used;

Figs. 10, 11 and 12 are respectively top, side and end views of the same end of the blank after excess material has been withdrawn from the drawn-out end;

40 Figs. 13, 14 and 15 are respectively top, side and end views of the same end of the blank after the drawn end of said blank has been bent up against the mandrel shown in Fig. 25 when the latter is placed in position in the upper part of dies shown in Figs. 21 and 22 and the plunger 23 is used;

Figs. 16, 17 and 18 are respectively top, side and end views of a completed horizontal body equalizer;

50 Figs. 19 and 20 are end and side views respectively of the hammer dies referred to in connection with Figs. 4, 5 and 6;

Figs. 21 and 22 are perspective views of the stationary forging machine dies referred

to in connection with the formation of portions shown in Figs. 7 to 18 inclusive;

Fig. 23 is a perspective view of the plunger used in bending up the end of the drawn portion of the blank to form and locate the second of the two cooperating jaws;

Fig. 24 is a perspective view of the plunger used in the upsetting step in forming the first jaw, as shown in Figs. 7, 8 and 9, and

Fig. 25 is a perspective view of the mandrel which acts as a spacer and against which the second jaw is pressed in the formation and location of said second jaw.

In following out the method, it will be understood that the metal blank or bar 30 shown in Figs. 1, 2 and 3 is first heated. Then one end of this blank 30 is subjected to a drawing-out process between the hammer dies 31 shown in Figs. 19 and 20. To give the blank the form shown in Figs. 4, 5 and 6, in which it will be noted that the end

70 of the blank is drawn out to form a horizontal projection 32 which is widened somewhat as shown in Fig. 6. An inclined shoulder 33 is roughly formed to which the top and bottom portions 34 and 35 taper, as

75 shown in Fig. 5, a tapered shoulder 36 also being formed. During this step to form the blank as shown in Figs. 4, 5 and 6, the blank is subjected to three passes in the hammer die, the first pass bringing into operation the die portion 37 having a relatively long taper, as shown in Figs. 19 and 20.

During the second pass the die portion 38 is brought into action, which has a steeper inclined portion. In the third hammer opera- 80

tion a straight horizontal portion 39 of the lower hammer dies is brought into action for gradually, in the three steps, giving the blank the shape shown in Figs. 4, 5 and 6.

After this step is over, the forging dies 95 40 are used. The blank, as shown in Figs. 4, 5 and 6, is placed in the lower die opening 41, so that the inclined shoulder 36 of the blank rests against the corresponding shoulder 36' in the die, and with the die 100 members 40 in their closed cooperating position, the plunger 42 (shown in Fig. 24) is passed through the opening 41 for upsetting that portion of the blank indicated by the roughly-formed inclined shoulder 33, 105 which may be considered a part of the drawn-out end of the blank. As a result of this step in the operation a straight, relative-

ly widened jaw 43 is provided, as shown in Figs. 7, 8 and 9, and the horizontal portion 32 is more accurately defined, the jaw 43 being formed at right angles to the portion 32.

5 On account of difficulty in gauging stock sufficiently accurately in the hammer operation to exactly fill the forging machine dies, it becomes necessary, where there is an excess of metal, to remove same. Such excess 10 metal is shown in a downwardly-extending projection 44, in Figs. 7, 8 and 9. This excess is then removed, preferably by shearing, thereby leaving the blank in the form shown in Figs. 10, 11 and 12. The blank, as shown 15 in Figs. 10, 11 and 12, is then placed in the upper openings 45 of the dies 40 so that the shoulder 36 engages the shoulder 36^a of the die and so that the back of the jaw 43 rests against the shoulders 46 of said dies. Then 20 the mandrel 47, shown in Fig. 25, is placed in the recesses 48 in said dies 40 as the latter are pressed to closed position, whereupon the plunger 49, shown in Fig. 23, is pressed inwardly in the die opening 45, and by means 25 of the pointed edge 50 the end 32 of the blank is bent up, whereupon the blunt end of the plunger 49 presses the drawn end 32 of the blank inwardly up against the mandrel 47, which acts as a spacer, and 30 whereby the second jaw is formed and located. Said second jaw is shown at 51 in Figs. 13, 14 and 15. The other end of the blank is treated in exactly the same way to produce the completed equalizer as shown 35 in Figs. 16, 17 and 18.

I claim:

1. A method for making an equalizer which consists in providing a blank, drawing out a portion of said blank, subjecting 40 said portion to pressure for upsetting some of it to form one of two cooperating jaws, then placing a mandrel adjacent said jaw to act as a spacer, and then bending the remaining portion of said drawn part up 45 against said mandrel to locate the other of said cooperating jaws.
2. A method for making an equalizer which consists in providing a blank, drawing out an end of the blank, subjecting said 50 drawn end to pressure for upsetting a portion of it to form one of two cooperating jaws, withdrawing excess metal from the drawn end, then placing a mandrel adjacent

said jaw to act as a spacer, and then bending the remaining portion of said drawn end up 55 against said mandrel to form and locate the other of said cooperating jaws.

3. A method for making an equalizer which consists in providing a blank, drawing out an end of the blank by the use of 60 hammer dies, subjecting said drawn end to pressure in a forging machine for upsetting a portion of it to form one of two cooperating jaws, then placing a mandrel adjacent said jaw to act as a spacer, and then bending the remaining portion of said drawn end up 65 against said mandrel to form and locate the other of said cooperating jaws.

4. A method for making an equalizer which consists in providing a blank, drawing out an end of the blank with hammer dies, subjecting said drawn end to pressure in a 70 forging machine for upsetting a portion of it to form one of two cooperating jaws, removing excess metal from the drawn end, 75 then placing a mandrel adjacent said jaw to act as a spacer, and then bending the remaining portion of said drawn end up against said mandrel to provide and locate the other of said cooperating jaws. 80

5. A method for making an equalizer which consists in providing a blank, drawing out an end of the blank by the use of hammer dies, subjecting said drawn end to pressure in a forging machine for upsetting said 85 blank to form one of two cooperating jaws, then placing a mandrel adjacent said jaw to act as a spacer, and then subjecting the remaining portion of said drawn end to pressure in a forging machine to move said end 90 up against said mandrel to provide and locate the other of said cooperating jaws.

6. A method for making an equalizer which consists in providing a blank, drawing out an end of the blank, subjecting said 95 blank to pressure for forming one of two cooperating jaws adjacent the inner end portion of said drawn out end, then placing a mandrel adjacent said jaw to act as a spacer, and then bending said drawn end up against 100 said mandrel to form and locate the other of said cooperating jaws.

Signed at Hammond, Indiana, this 8th day of May, 1925.

LOREN L. WHITNEY.
